UNITED STATES PATENT OFFICE.

ERASTUS E. WINKLEY, OF LYNN, MASSACHUSETTS.

CUTTING-MACHINE.

1,122,561.

Specification of Letters Patent. Patented Dec. 29, 1914.

Application filed August 1, 1908. Serial No. 446,423.

To all whom it may concern:

Be it known that I, ERASTUS E. WINKLEY, citizen of the United States, residing at Lynn, in the county of Essex and State of Massachusetts, have invented certain new and useful Improvements in Cutting-Machines; and I do hereby declare the following to be a full, clear, and exact description of the invention, such as will enable others skilled in the art to which it appertains to make and use the same.

The invention relates more particularly to a machine for cutting out articles having an irregularly curved outline, such for instance as shoe soles, from rubber compounds or other plastic material, although various features of the invention may be embodied in machines for forming other articles or performing various operations in which the operating tool is caused to travel in an irregularly curved path.

Soles for rubber boots or shoes are cut from a sheet of rubber compound which is plastic and easily stretched or distorted, and machines designed for cutting such soles have proved unsatisfactory, either for the reason that the material has not been properly held against distortion by the cutter, or for the reason that the holding means has been of such a character as to disfigure or distort the sole.

One object of the present invention is accordingly to provide means for properly holding the material during the action of the cutter without subjecting the sole to a distorting or disfiguring pressure.

To this end one feature of the invention contemplates the provision in a machine for cutting articles from plastic material of means for progressively clamping the material at the cutting point as the point of operation of the cutter is transferred along the outline of the sole.

In forming articles such as rubber soles, the surface of which should not be marked or indented by the holding means, the material is clamped by engagement with the material outside or on the waste side of the line of cut, and another feature of the invention contemplates the provision of means for thus clamping the material. It is not essential to this feature of the invention that the clamping pressure should be applied progressively, and the invention contemplates the provision of any form of clamping de-

vices constructed to hold the material during the travel of the cutter by engagement with the waste material outside the line of cut.

A further feature of the invention contemplates the provision in a machine in which the cutter travels along the material during the cutting operation of means acting upon the material adjacent to the cutting point to counteract the distorting action of the knife and thus insure the proper cutting of the material.

In accordance with the features of the invention above referred to, the relative movement between the material and cutter requisite for giving the proper outline to the sole or other article being cut may be effected by any mechanism constructed and arranged to cause the travel of the cutter to conform to the cutting of the article being produced. I prefer, however, to employ a novel form of mechanism for this purpose, which embodies various further features of invention. In accordance with one of these features of invention, the travel of the cutter is effected by a feeding device connected with the cutter, and acting by engagement with the material adjacent to the cutting point to move the cutter along the material. The feeding device in its preferred form consists of a wheel arranged to engage the waste material outside the line of cut, and this wheel may and preferably does act as the clamping means as well as the feeding means, and also as the means for counteracting the distorting action of the knife, although such construction is not essential to the broader features of the invention.

The features of the invention relating to the construction and arrangement of the tool and feeding means is not confined in its application to machines for performing a cutting operation, or to machines for acting upon plastic materials, but may be embodied in various machines in which a tool comprising either a single device, such as a cutter, or comprising a combination of co-operating devices for operating upon the work, is to be caused to travel along the work in a prescribed path.

The construction and arrangement of the means for controlling the movement of the cutter or other tool, so that it will travel in the prescribed path, is not material to the invention in its broader aspects. In its preferred form, however, the invention con-

templates the employment for this purpose of a mechanism embodying certain further features of invention which are not confined in their application to a machine for cutting plastic material, but may be embodied in various machines in which the devices for operating upon the work are caused to travel in a path corresponding to the outline of a form or pattern. In accordance with one of these features, the path of travel of the tool along the material is determined by a form or pattern and a gage which is connected with the tool and is held in engagement with the form during the relative movement of the tool and material by means which acts on the material. In its preferred form the means which acts upon the material consists of a feed wheel which is so controlled that it acts by engagement with the material to cause the travel of the tool along the material, and to keep the gage in contact with the form during such travel.

In addition to the features of invention above outlined, the invention includes certain further features and combinations which will be more particularly pointed out in the claims.

The various features of the invention will be readily understood from an inspection of the accompanying drawings, in which—

Figure 1 is an end elevation of a machine embodying the various features of the invention in their preferred form, and designed especially for cutting soles for rubber boots and shoes; Fig. 2 is a front elevation of the machine; Fig. 3 is a rear elevation; Fig. 4 is a plan view; Fig. 5 is a detail plan view of certain parts of the controlling mechanism; Fig. 6 is a rear elevation of the parts shown in Fig. 5; Fig. 7 is a sectional elevation on line 7—7, Fig. 5, looking toward the left; Fig. 8 is an enlarged detail plan view showing a part of the form or pattern and the devices engaging therewith; Fig. 9 is a detail elevation showing the cutter carrying head; Fig. 10 is a sectional plan view on line a—b, Fig. 11; and Fig. 11 is a rear sectional elevation of the parts shown in Fig. 9.

In the construction shown, the material to be operated upon consists of a sheet A of rubber compound, and this material is supported upon a work supporting plate 1 which is preferably formed of glass, and to which the under surface of the rubber sheet adheres when the sheet is placed in position. As shown, the work supporting table 1 is pivotally supported at 2, and is held in position by a spring 3. The work supporting table is connected by means of a rod 4 with a treadle by which the table may be depressed for the purpose of removing the work, or placing a fresh sheet of material upon the table.

The work is supported by the work support 1 in position to be acted upon by a cutter 5 and feed wheel 6 mounted upon a head which is supported for free bodily movement over the work. In order that the head may be free to move in any direction over the work, it is carried in the outer end of a frame 7, the other end of which is pivotally supported upon a vertical shaft 8 mounted in the end of a second frame 9, which is in turn pivotally supported upon a vertical shaft 10 mounted in fixed bearings on the frame of the machine. The feed wheel 6 is mounted in a supporting frame 11 secured to the lower end of a shaft 12 which is mounted in the outer end of the frame 7. This wheel is rotated during the operation of the machine through a sleeve 13 which surrounds the shaft 12, and is provided at its lower end with a worm 13' engaging a worm wheel 14 which is connected through gearing 15 with the feed wheel. The work carrying sleeve 13 is driven from the shaft 10 through sprocket chains 16 and 17. The chain 17 passes over a sprocket wheel 18 secured to the sleeve 13, and over a sprocket wheel 19 which is mounted on the shaft 8 and is connected with a second sprocket wheel 20 about which the sprocket chain 16 passes. The chain 16 also passes about a sprocket wheel 21 which is connected with a gear 22 mounted on the shaft 10, and driven from the driving shaft 23 through the gear 24. The feed wheel is arranged with its axis intersecting the axis of the shaft 12, and is preferably arranged with the side which is toward the cutter substantially in the axis of the shaft 12, although such arrangement is not essential.

The cutter 5 is in the form of a knife blade arranged at an inclination to the work support 1, so that the edge of the sole is cut on a bevel, as is usual in cutting rubber soles. The knife is preferably arranged so that it enters the work in line with the point of engagement of the feed wheel with the work, and so that its point of operation practically coincides with the axis of the shaft 12. The cutter is secured in an arm 25 which is pivotally connected at 26 with a cutter carrier 27, and is held normally in position against a lug 28 on the carrier by a pivoted latch 29. During the cutting operation, the cutter carrying arm 25 is locked in fixed position upon the carrier by the latch 29. When the work is to be inserted, the latch 29 is swung to one side so that the cutter may be raised, and after the work is positioned between the feed wheel and work support, the arm 25 is swung down to insert the cutter in the work, and is locked in position by the latch 29. In order that the cutter may have a limited vertical movement so that its point will travel in engagement with the work support at all times

during the cutting operation, the cutter carrier is so mounted that it may move vertically and is held in its lower position by a spring. As shown, the cutter carrier is 5 provided with a hub 30 which surrounds a cylindrical bearing 31 formed on the under side of the frame 7 concentric with the shaft 12. The lower end of the hub is yieldingly held in engagement with a collar 32 secured on the lower end of the bearing 33 by means of a spring 34, one end of which is connected to a pin 34 on the hub, and the other end of which is connected with a pin 35 on the frame which carries the feed wheel. In order that the knife may 10 be maintained in proper relation to the line of travel, as its point of operation is transferred along the work, the cutter carrier 27 is connected with the frame 11 by means 15 of a pin 36 which projects from the frame 11 into a vertical slot 37 formed in the cutter carrier. By means of this connection, the cutter is swung about the axis of the shaft 12 to keep the cutter tangent to the line of 20 cut as the shaft is turned to vary the direction of action of the feed wheel upon the work in the manner hereinafter described.

The work is forced against the under surface of the feed wheel 6 by the spring 3 25 which forces the work support 1 upward, and the rotation of the feed wheel while in engagement with the work tends to move the head which carries the feed wheel and cutter with relation to the work in a direction 30 depending upon the angular position of the feed wheel. The action of the feed wheel against the material being operated upon tends to force the material in a direction 35 opposite to the travel of the feed wheel 40 and knife, and therefore tends to move the material in a direction opposite to that in which the material is forced by the action of the knife. Since the wheel acts upon the material adjacent to the cutting point, the 45 tendency of the knife to distort the material is counteracted, and the material is effectively held against distortion as the cutter is drawn through the material. The feed wheel is arranged to engage the material 50 outside of the point of operation of the knife, and the material entering into the sole is not therefore subjected to any clamping pressure tending to disfigure or distort it. Since the feed wheel is arranged 55 to engage the work adjacent to the point of operation of the cutter, it acts as it travels over the work to progressively clamp the material as that point is transferred along the outline of the sole.

60 The path of travel of the feed wheel and cutter is determined by a form or pattern 38 which corresponds in shape and size to the sole to be cut. This form is secured upon the under side of a supporting bar 39, and may be changed in accordance with 65 the size and style of sole to be cut. The form is arranged above the work support and the shaft 12 of the head which carries the cutter and feed wheel is provided with a gage finger 40 adapted to travel about 70 the periphery of the form. The bearing surface of the gage is arranged in the axis of the shaft 12, so that the point of engagement of the gage with the form corresponds to the point of operation of the 75 cutter upon the material being cut.

In order that the movement imparted to the cutter carrying head by the feed wheel acting against the material being operated upon may correspond to the outline of the 80 form 38, the angular relation of the feed wheel should be varied as the point of operation is transferred along the outline of the sole to cause the line of action of the feed wheel, or the direction of the feed, to 85 correspond to the outline of the form. In order that the angular relation of the feed wheel may be thus varied, mechanism is provided for controlling the angular relation of the feed wheel by the curvature of 90 the form 38. As shown, this means includes a feeler 41 in the form of a finger pivoted at 42 to the upper end of the shaft 12, and arranged to engage the periphery of the form 88 in advance of the point of engagement of 95 the gage finger 40 with the form, and therefore in advance of the point of operation of the knife upon the sole being cut. The position of this feeler finger with relation to the gage finger will depend upon the curvature 100 of the form in advance of the point of operation, and mechanism is provided, the action of which is controlled by the position of the finger for varying the line of action of the feed wheel in accordance with the 105 position of the feeler finger, so that the line of action or direction of the feed will correspond to the outline of the form. The line of action of the feed wheel or the direction of the feed is varied by rotating the shaft 12 110 in one direction or the other, according to the curvature of the form at the point corresponding to the point of operation of the knife. Movements are imparted to the shaft 12 to vary the direction of the feed 115 through a sprocket chain 43 which passes about a sprocket wheel 44 secured to the shaft 12, and about a sprocket wheel 45 mounted to turn freely on the shaft 8. The sprocket wheel 45 is connected with 120 a sprocket wheel 46 engaged by a sprocket chain 47 which also passes about a sprocket wheel 48 mounted to turn freely on the shaft 10. The sprocket wheels are of uniform diameter, and these wheels and chains 125 form connecting devices which hold the shaft 12 and connected head in the same angular relation as the head is moved in the plane of operation, so that the movements imparted to the head by the feeding device 130

have no effect upon the angular relation of the head. The sprocket wheel 48 is connected with a gear 49 which is engaged and operated by a gear 50 secured to a hollow shaft 51. The hub of the gear 50 is provided with a radially extending arm 52 which carries a pawl 53 through which the gear 50 is operated to vary the angular relation of the shaft 12 and feeding wheel and cutter. The pawl 53 is arranged to be intermittently engaged with the teeth of a ratchet wheel 54, the movements of which are controlled by the engagement of the feeler finger 41 with the form 38. The engagement of the pawl 53 with the ratchet wheel 54 is controlled through a lever 55, one end of which engages a rod 56 mounted within the hollow shaft 51, and the other end of which engages a projection 57 on the pawl. The lower end of the rod 56 is engaged by one end of a lever 58, the other end of which carries a roll engaging a cam 59 secured to the driving shaft 23. When the pawl 53 is out of engagement with the ratchet wheel 54, the gear 50 is clamped in position so as to prevent change in the angular relation of the shaft 12 and head carried thereby under the action of the feeding wheel in feeding the head. The means for thus maintaining the angular position of the feeding wheel when the controlling mechanism is out of action comprises a clamp 60 secured to the upper end of a rod 61, the lower end of which is connected to one arm of a bell crank lever 62. The other arm of the bell crank lever is connected by a link 63 with one arm of a bell crank lever 64, the other arm of which carries a roll arranged to engage a cam 65 secured to the shaft 23. A spring 66 surrounding the link 63 tends to force the clamp 60 against the gear 50, and the clamp is disengaged from the gear by the cam 65.

The mechanism for operating the ratchet wheel 54 through which movements are imparted to the shaft 12 comprises a pinion 67 secured to the gear 54 and engaged by a segment 68 formed on the rear end of a lever 69. The front end of the lever carries a roll 70 arranged to be engaged and operated by oppositely inclined actuating surfaces 71 formed on the front end of an actuating slide 72. The actuator slide 72 is operated through a lever 73, one end of which is connected by a link 74 with the slide, and the other end of which carries a roll 75 held in engagement with a cam 76 on the shaft 23 by a spring 77. When the actuator slide 72 is advanced, the actuating pawl 53 is in engagement with the ratchet wheel 54, and the ratchet wheel will be operated to turn the shaft 12 in one direction or the other according to the position of the roll 70 with relation to the actuating surfaces 71, the shaft 12 being turned in one direction if the roll

is in position to be engaged by one of the actuating surfaces 71, and being moved in the opposite direction if the roll is in position to be engaged by the other actuating surface. If the roll 70 is in register with the recess 78 between the actuating surfaces 71, then no movement will be imparted to the lever 69 and connected ratchet wheel and pawl, and no change in the angular position of the shaft 12 will be effected by the advance movement of the actuator slide.

The position of the roll 70 when the actuator slide advances is controlled by the feeler finger 41 through the following mechanism. The finger 41 is provided with a horizontally extended arm 79 which engages a circular flange 80 formed on a sleeve 81 which is mounted on the head shaft 12 and is supported by a light spring 82. The under side of the flange 80 engages the front end of a lever 83, the rear end of which engages the under surface of a flange 84 formed on a sleeve 85 which is mounted to slide freely upon the upper end of the shaft 8. The flange 84 underlies the front end of a lever 86, the rear end of which engages the upper surface of a flange 87 formed on a sleeve 88 which is mounted to slide freely on the upper end of the shaft 10, and is supported by a light spring 89. Through these connections the vertical position of the sleeve 88 is controlled by the engagement of the feeler finger 41 with the periphery of the form 38. The position of the sleeve 88 determines the position of the roll 70 when the actuator slide 72 is advanced. The devices through which this control is effected comprise a roll 90 carried by the sleeve 88, and mounted to be engaged by two oppositely inclined actuating surfaces 91 formed on the front end of an actuator slide 92. The actuator slide is mounted in a lever pivoted at 93, and provided with a vertically extending arm 94. The arm 94 carries a roll 95 which engages an annular groove 110 formed in a sleeve 96 which is mounted to slide on a fixed rod 97. The sleeve 96 is connected by a link 98 with the lever 69 which carries the roll 70. The actuator slide 92 is reciprocated at proper intervals 115 through a bell crank lever 99, one end of which is connected by means of a link 100 with the slide 92, and the other end of which is provided with a roll 101 engaging a cam 102 secured to the shaft 23. The sleeve 88 which carries the controlling roll 90 is clamped in position during the advance of the actuator slide 92 by a clamping lever 103 arranged to engage a rib 104 formed on the sleeve. The clamping lever is actuated 120 to clamp the sleeve by a spring 105, and is operated to release the sleeve through a lever 106 which is operated by a cam 107 secured to the shaft 23.

If the roll 90 is in position to be engaged 130

by either of the actuating surfaces 91 when the actuator slide 92 is advanced, the lever carrying the slide will be rocked in one direction or the other, according to the position of the roll 90, and the rocking of the lever will shift the roll 70 into position corresponding to the position of the roll 90. The cams for operating the different parts are so timed that the pawl 53 is out of engagement with the ratchet wheel 54 during the locating of the roll 70, and is engaged with the ratchet wheel immediately after the roll is located, and before the actuator slide 72 is advanced.

15 The cam shaft 23 is rotated at a comparatively high rate of speed, and the action of the cams is so timed with relation to the rotation of the feed wheel that the rotation of the head shaft 12 to vary the direction of the feed is effected during the advance of the gage finger 40 through the distance between the gage finger and the feeler finger 41. The feeler finger thus acts in advance of the point of operation upon the work to determine the required change in the direction of the feed, and the controlling mechanism acts to effect this change as the point of operation is advanced to the point corresponding to the position of the feeler finger, so that the direction of feed is accurately controlled in accordance with the curvature of the controlling form. The controlling mechanism is operated during each rotation of the shaft 23, and the cycle of operations performed during each rotation of this shaft is as follows. Assuming that the sleeve 88 has been positioned by the engagement of the feeler finger 41 with the form 38, and the clamp 103 has been operated to clamp the sleeve in position, the actuator slide 93 is advanced, and the lever on which the slide is mounted is rocked during this advance in accordance with the position of the roll 90 on the sleeve 88, and by this movement positions the roll 70 on the lever 69. While the sleeve 88 is still clamped, and the actuator slide 92 is advanced, the clamp 60 is operated to release the gear 50, and the pawl 53 is engaged with the ratchet wheel 54. The actuator slide 92 is then retracted, and the controller sleeve 88 unclamped, so that it may be again positioned by the feeler finger 41. As the actuator slide 92 is retracted, or immediately thereafter, the actuator slide 72 is advanced, and by the engagement of the actuator surfaces 71 with the roll 70, swings the lever 69 into position where the roll 70 enters the recess 78 between the actuator surfaces, and thus turns the ratchet wheel 54 in one direction or the other to change the angular position of the head carrying shaft 12 in accordance with the curvature of the form 38. When the actuator slide 72 has completed its advance movement, the pawl 53 is disengaged from the ratchet 54, and the clamp 60 is engaged with the gear 50, and then the slide is returned to its rearward position. The clamp 103 is then operated to again clamp the sleeve 88 in the new position which has been determined by the engagement of the feeler finger 41 with the form 38, and the cycle of operations is repeated. Thus the line of action of the feeding wheel is controlled and varied so that the gage 40 on the head which carries the feed wheel and cutter travels about the form 38, and during this travel the head is turned to keep the direction of feed in line with the periphery of the form at the point corresponding to the point of operation, and to vary the position of the knife so that it is tangent to the curve of the sole at the point of operation throughout the cutting operation.

20 Having explained the nature and object of the invention, what I claim is:—

1. A cutting machine, having, in combination, a cutter, means for causing a travel of the cutter corresponding to the outline of the article to be cut, and means for progressively clamping the material adjacent to the cutting point, as said point is transferred along the material, substantially as described.

2. A cutting machine, having, in combination, a cutter, means for causing a travel of the cutter corresponding to the outline of the article to be cut, and means for progressively clamping the material by engagement therewith outside the cutting point as said point is transferred along the material, substantially as described.

3. A machine for cutting sheet rubber, having, in combination, a cutter, means for causing a travel of the cutter corresponding to the outline of the article to be cut, and a clamping wheel traveling with the cutter and arranged to engage the rubber substantially at the cutting point and prevent distortion by the cutter, substantially as described.

4. A machine for cutting sheet rubber, having, in combination, a cutter, means for causing a travel of the cutter corresponding to the outline of the article to be cut, and a clamping wheel traveling with the cutter and arranged to engage the material substantially at the cutting point and outside of the line of cut to prevent distortion by the cutter, substantially as described.

5. A machine for cutting sheet material, having, in combination, a work support, a traveling knife blade, and means acting upon the material on the support to draw the knife blade through the material, substantially as described.

6. A cutting machine, having, in combination, a traveling knife, and means acting upon the material adjacent to the cutting

- point in opposition to the cutter to counteract the distorting action of the knife, substantially as described.
7. A cutting machine, having, in combination, a traveling cutter, and means acting on the material substantially at the cutting point in opposition to the cutter to draw the cutter through the material, substantially as described.
10. A machine for cutting sheet material, having, in combination, a work support, a cutter, a feeding device connected with the cutter and engaging the material on the work support, and means for actuating the feeding device to feed the cutter bodily along the material on the support, substantially as described.
15. A cutting machine, having, in combination, a cutter carriage, a cutter mounted in the carriage, a feeding wheel mounted in the carriage acting by engagement with the material to be cut to draw the cutter through the material, and means for turning the wheel in the carriage to vary the direction of travel, substantially as described.
20. A machine, having, in combination, a work support, a carriage mounted to move freely in any direction over the work support, a tool mounted in the carriage, feeding means acting by engagement with the material on the support to cause a travel of the carriage over the material, and means for automatically controlling the feeding means to determine the path of travel, substantially as described.
25. A machine, having, in combination, a carriage mounted to move freely in any direction in the operating plane, a tool mounted in the carriage, a feed wheel for causing the travel of the carriage along the work, and controlling mechanism for turning the wheel to determine the path of travel, substantially as described.
30. A machine, having, in combination, a tool, a feeding wheel acting to cause a travel of the tool along the work, a form, and means for varying the line of action of the feeding wheel in accordance with the curvature of the form, substantially as described.
35. A machine, having, in combination, a tool carrying head mounted for movement in a plane parallel with the plane of the material being operated on, feeding means mounted in the head, a form, and means controlled by the curvature of the form to turn the feeding means in conformity with said curvature, substantially as described.
40. A machine, having, in combination, a form, a tool, feeding means for effecting a movement of the tool in the direction of the periphery of the form, and mechanism controlled by the periphery of the form for swinging the feeding means in accordance with the outline of the form, substantially as described.
45. A machine, having, in combination, a tool, a form, feeding means for effecting a movement of the tool in the direction of the periphery of the form, and mechanism controlled by the periphery of the form for swinging the tool and feeding means in accordance with the outline of the form, substantially as described.
50. A machine, having, in combination, a tool, a form, feeding means for moving the tool to transfer the point of operation along the work, and mechanism controlled by the periphery of the form acting to turn the feeding means and tool about the point of operation of the tool to cause the travel of the tool to correspond with the outline of the form, substantially as described.
55. A machine, having, in combination, a form, a tool, feeding means acting to cause a travel of the tool, a feeler engaging the form, and mechanism controlled by the feeler for varying the angular position of the feeding means in accordance with the curvature of the form, substantially as described.
60. A machine, having, in combination, a form, a tool carrying head, a gage on the head engaging the form, feeding means acting to cause a travel of the head, a feeler arranged to engage the form in advance of the gage, and mechanism controlled by the feeler for varying the line of action of the feeding means in accordance with the curvature of the form, substantially as described.
65. A machine, having, in combination, a form, a tool carrying head, a feed wheel mounted in the head and acting to cause a travel of the head, a form, a gage connected to travel with the head and engaging the form, and means for controlling the angular position of the feed wheel by the curvature of the form, substantially as described.
70. A machine, having, in combination, a tool carrying head, a feed wheel mounted in the head and acting to cause a travel of the head, a form, a gage traveling with the head and engaging the form, a feeler arranged to engage the periphery of the form in advance of the gage, and mechanism controlled by the feeler for varying the angular position of the feed wheel in accordance with the curvature of the form, substantially as described.
75. A machine, having, in combination, a tool carrying head, a feed wheel mounted in the head and acting to cause a travel of the head, a form, a gage connected to travel with the head and engaging the form, and means for controlling the angular position of the feed wheel by the curvature of the form, substantially as described.
80. A machine, having, in combination, a form, a tool carrying head, a gage on the head engaging the form, feeding means acting to cause a travel of the head, a feeler arranged to engage the form in advance of the gage, and mechanism controlled by the feeler for varying the line of action of the feeding means in accordance with the curvature of the form, substantially as described.
85. A machine, having, in combination, a form, a tool carrying head, a feed wheel mounted in the head and acting to cause a travel of the head, a form, a gage connected to travel with the head and engaging the form, and means for controlling the angular position of the feed wheel by the curvature of the form, substantially as described.
90. A machine, having, in combination, a tool carrying head, a feed wheel mounted in the head and acting to cause a travel of the head, a form, a gage connected to travel with the head and engaging the form, and means for controlling the angular position of the feed wheel by the curvature of the form, substantially as described.
95. A machine, having, in combination, a tool carrying head, a feed wheel mounted in the head and acting to cause a travel of the head, a form, a gage connected to travel with the head and engaging the form, and means for controlling the angular position of the feed wheel by the curvature of the form, substantially as described.
100. A machine, having, in combination, a tool carrying head, a feed wheel mounted in the head and acting to cause a travel of the head, a form, a gage connected to travel with the head and engaging the form, and means for controlling the angular position of the feed wheel by the curvature of the form, substantially as described.
105. A machine, having, in combination, a tool carrying head, a feed wheel mounted in the head and acting to cause a travel of the head, a form, a gage traveling with the head and engaging the form, a feeler arranged to engage the periphery of the form in advance of the gage, and mechanism controlled by the feeler for varying the angular position of the feed wheel in accordance with the curvature of the form, substantially as described.
110. A machine, having, in combination, a tool carrying head, a feed wheel mounted in the head and acting to cause a travel of the head, a form, a gage traveling with the head and engaging the form, a feeler arranged to engage the periphery of the form in advance of the gage, and mechanism controlled by the feeler for varying the angular position of the feed wheel in accordance with the curvature of the form, substantially as described.
115. A machine, having, in combination, a tool carrying head, a feed wheel mounted in the head and acting to cause a travel of the head, a form, a gage traveling with the head and engaging the form, a feeler arranged to engage the periphery of the form in advance of the gage, and mechanism controlled by the feeler for varying the angular position of the feed wheel in accordance with the curvature of the form, substantially as described.
120. A machine for operating on sheet material, having, in combination, a tool, a form, a gage connected with the tool and bearing against the form, and means acting on the material to keep the gage in contact with the form during the relative movement of the tool and material, substantially as described.
125. A machine for cutting sheet rubber, having, in combination, a cutting knife, and a feed wheel bearing upon the rubber outside of the line of cut and adjacent the cut.

ting point, said wheel acting to cause the knife to travel through the rubber and to prevent the distortion of the rubber by the cutting knife, substantially as described.

5 23. A cutting machine, having, in combination, a cutter, and means acting upon the material to cause a travel of the cutter corresponding to the outline of the article to be cut, and for progressively clamping 10 the material by engagement therewith adjacent to the cutting point, substantially as described.

24. A cutting machine, having, in combination, a cutter, and a feed wheel bearing 15 upon the material adjacent to the cutting point and acting to draw the cutter bodily through the material, substantially as described.

25. A machine, having, in combination, a 20 form, a traveling tool, feeding means acting to cause the travel of the tool, a feeler engaging the form, and mechanism controlled by the feeler for varying the angular relation of the tool, substantially as described.

25 26. A machine, having, in combination, a traveling tool carrying head, a form, a gage

on the head engaging the form, a feeler arranged to engage the form in advance of the gage, and mechanism controlled by the feeler for varying the position of the 30 tool in accordance with the variations in the position of the feeler as the gage travels around the form, substantially as described.

27. A machine, having, in combination, a 35 tool, a form, a gage connected with the tool and bearing against the form, a feeler engaging the form in advance of the gage, and mechanism controlled by the feeler for causing the gage to travel along the form, substantially as described. 40

28. A machine, having, in combination, a stationary form, a traveling gage, feeding means acting to transfer the gage along the form, a feeler, and mechanism controlled by the feeler to keep the gage and form in contact, substantially as described. 45

In testimony whereof I affix my signature, in presence of two witnesses.

ERASTUS E. WINKLEY.

Witnesses:

EDWARD S. DAY,
WARREN G. OGDEN.
